United States Patent Office.

QUIMBY S. BACKUS, OF WINCHEON, MASSACHUSETTS.

Design No. 3,130, dated July 28, 1868.

DESIGN FOR A VISE.

The Schedule referred to in these Letters Patent and making part of the same.

TO ALL WHOM IT MAY CONCERN:

Be it known that I, QUIMBY S. BACKUS, of Winchendon, in the county of Worcester, and State of Massachusetts, have originated and designed a new Pattern for Vises, of which the following is a full, clear, and exact description, reference being had to the accompanying drawings, making part of this specification, in which—

Figure 1 is a perspective of a vise of my new pattern.

Figure 2 is a longitudinal vertical section through the centre of the same.

Figure 3 is a transverse vertical section on the line $x\ x$ of fig. 2.

My new invention or production consists in the pattern for a vise.

To enable others skilled in the art to understand and produce my invention, I will proceed to describe the manner in which I have carried it out.

In the said drawings, a circular plate, B, forms the bed, upon which rests the stationary jaw C, a spindle, a, passing up through the bench A and plate B.

The portion c of the stationary jaw C, upon which the upper jaw D is moved, is of the form and of the pattern shown in figs. 1 and 3, being that of an arc of a circle from 4 to 5, from which points the tines descend about vertically to the points 6, the peculiar form or pattern being chiefly that of an arc.

E F are tubes, one end of each of which is secured to one of the jaws, one tube sliding within the other.

What I claim as my invention, and desire to secure by Letters Patent, is—

The design or pattern for a vise, herein set forth and shown.

QUIMBY S. BACKUS.
